VOTIVE ALTAR FOR A VEHICLE OR THE LIKE

Kenneth W. Caldwell, Campbell, Calif.
(55 Glen Eyrie Ave., San Jose, Calif. 95125)

Filed Jan. 26, 1967, Ser. No. 5,576

Term of patent 14 years

(Cl. D29—23)

FIG. 1.

FIG. 5.

FIG. 2.

FIG. 6.

FIG. 3.

FIG. 4.

FIG. 1 is a perspective view of a votive altar for a vehicle or the like and embodying my new design.

FIG. 2 is a top plan view of the votive altar shown in FIG. 1.

FIG. 3 is a front elevational view of the same.

FIG. 4 is a back elevational view of the same.

FIG. 5 is a side elevational view of the same as seen from the righthand side of the FIG. 3.

FIG. 6 is a side elevational view of the same as seen from the righthand side of FIG. 4.

The essential features of the design are shown in solid lines.

I claim:

The ornamental design for a votive altar for a vehicle or the like, as shown and described.
